TOOTH BRUSH

Andrew J. Planding, New York, N. Y.

Application January 18, 1934, Serial No. 707,158

2 Claims. (Cl. 15—110)

My present invention in its broad aspect has to do with improvements in tooth brushes, and more particularly it is my purpose to provide in conjunction with the tufts of bristles a plurality of rubber members in the interproximal spaces which function to massage the gums, more completely cleanse the teeth after the manner of a squeegee, more effectively support the bristle tufts to prevent them from flattening out, and to otherwise provide a greatly improved and more efficient instrument for cleaning and caring for the teeth.

I am aware that it is broadly old to provide a rubber device for cleansing and massaging the teeth, but in the prior proposed devices with which I am acquainted there is a tendency to retain and harbor foreign matter, and there is also a tendency to induce abrasive action, and the positioning of the cleansing members is such that the spaces between the teeth are not properly cleaned.

My present device, on the other hand, contemplates the use of both bristles and rubber, preferably in an alternate arrangement so that the benefits of both are retained, and other advantages attained which are not possible where either rubber or bristles are used alone. Briefly outlined, the principal advantages of my invention are; first, to provide means for massaging the gums when the teeth are brushed so that a healthy condition of the gums as well as clean teeth is attained; second, to provide rubber devices in the interproximal spaces between the bristle tufts so that the teeth are more thoroughly cleaned; third, to support the bristles in an effective position for cleansing by means of the reinforcement or supporting action of the rubber members, and fourth, to so form the rubber and bristle members that the close spaces between the teeth are reached as well as the surface areas.

Other and equally important objects and advantages of my invention will appear as the detailed description proceeds, but in that connection it is to be understood that the scope of my invention is only to be determined by reference to the claims appended hereunto.

In the drawing wherein is shown the principal form, and several modifications of my invention;—

Figure 1 is a side elevation of a tooth brush of the refillable type, showing the preferred arrangement of bristles and rubber members;

Figure 2 is a plan view of the same;

Figure 3 is a detail section showing the bristle tuft and rubber members;

Figure 4 is a modification showing the alternate

arrangement of bristle tufts and rubber members extending completely across the face of the brush;

Figure 5 is a modification showing the bristle tufts and rubber members arranged in spaced apart rows;

Figure 6 is a modification showing the bristle tufts and rubber members arranged in staggered rows;

Figure 7 shows a rubber member set in the brush head, and

Figure 8 shows a rubber member partially removed from the brush head.

In the drawing wherein like characters of reference are used to designate like or similar parts throughout the several views;—

The numeral (1) designates the handle of a tooth brush, and (2) the head part thereof. The bristle or brush mounting is designated by the numeral (3), and the eye in the handle by (4). These parts are conventional and may be of any desired shape, size or material.

In the preferred form of my invention shown in Figures 1 and 2 and 3 the bristle tufts (5) and rubber members (6) alternate, and the rubber members are wedge shaped as shown with the bristle tufts slightly above the rubber members and substantially filling the inter-proximal spaces. If desired the brush head may be formed with holes (7)—see Figures 7 and 8, and the rubber members formed with shanks (8) and heads (9) so that by pushing the shanks through the holes as shown in Figure 8, the heads (9) will engage in the countersunk groove (10) about the bottom of each hole to properly hold the rubber members in place; this form of mounting also permits replacing rubber members when they become worn or old.

The advantages of this form of my invention are that it is easily kept clean; will properly massage the gums; properly clean the teeth and that includes the hidden spaces and between the teeth; the bristle tufts are properly supported by the rubber members, and the fine edge of the rubber members has a squeegee effect.

Figures 4, 5 and 6 show modifications of my invention. In Figure 4 the alternate bristle and brush members are shown as extending completely across the face of the tooth brush, whereas in Figures 1 and 2, these are arranged in two rows. Figure 5 shows the bristle and brush members arranged in more than two spaced rows. Figure 6 shows the rows of bristles and tufts in relatively staggered relationship. Attention is directed to the fact that in my present invention the essential features are that the bristle tufts

rise above the ends of the rubber members, and the bristles flare out between the interproximal spaces between the wedge shaped rubber members to substantially fill said spaces, whereas the 5 beveled ends of the bristle members above the rubber members serving to thoroughly cleanse the spaces between the teeth, while the squeegee effect of the rubber members is to polish and cleanse the plane surfaces of the teeth. The 10 maximum effect is in the combination of the two cleansing elements in a unitary brush.

In practice the brush is operated in the usual way and has all of the advantages herein attributed to it, but since certain changes may be made 15 in form and arrangement it is again pointed out that such changes are permissible provided they fall within the scope of what is claimed.

I claim:—

1. A tooth brush designed to produce a combined brushing and squeegee effect, comprising alternate rows of bristle tufts and rubber members, the bristle tufts rising above the rubber members to lightly engage the teeth and cleanse between the spaces thereof before said teeth are 20 engaged by the rubber members, and said tufts

being beveled above said rubber members to a point, said rubber members being wedge shaped in vertical cross section, and the bristle tufts being flared outwardly from their bases to the tops of the rubber members in conformity with 5 the shape of the interproximal spaces between the rubber members.

2. A tooth brush designed to produce a combined brushing and squeegee effect, comprising alternate rows of bristle tufts and rubber members, the bristle tufts rising above the rubber members to engage the teeth when the brush is first applied to lightly brush the teeth and cleanse between the spaces thereof before said teeth are engaged by the rubber members, and 15 said tufts being beveled above said rubber members to a point, said rubber members being wedge shaped in vertical section and rectangular in cross-section and disposed with their bases against the head of the brush, and the bristle tufts being flared outwardly from their bases to the tops of the rubber members in conformity with the shape of the interproximal spaces between the rubber members.

ANDREW J. PLANDING. 25
